UNITED STATES PATENT OFFICE.

HENRY H. BURNS, OF BATTLE CREEK, MICHIGAN, ASSIGNEE, BY MESNE ASSIGNMENTS,
TO T. D. PALMER, OF SYRACUSE, NEW YORK.

PRESSING-MACHINE.

1,023,066.

Specification of Letters Patent.

Patented Apr. 9, 1912.

Application filed February 18, 1909. Serial No. 478,673.

To all whom it may concern:

Be it known that I, HENRY H. BURNS, a citizen of the United States of America, residing at Battle Creek, in the county of Calhoun and State of Michigan, have invented certain new and useful Improvements in Pressing-Machines, of which the following is a specification, reference being had thereto in the accompanying drawings.

10 The invention relates particularly to a garment pressing machine, and consists in the construction thereof, in the peculiar arrangement and combination of its parts, and in various details of construction, as 15 will be more fully hereinafter set forth.

In the drawings,—Figure 1 is a side view of the machine, showing the upper part in elevation and the lower portion in vertical section; Fig. 2 is a rear elevation; Fig. 3 is a 20 view, partly in section and in elevation, of the lower front portion of the machine, illustrating the adjusting mechanism for the buckboard and the locking means for the supplemental table; Fig. 4 is an enlarged detached view of the buckboard, 25 partly in section; Fig. 5 is a similar view of the presser head; Fig. 6 is a cross section through the head; Fig. 7 is a bottom plan view, partly broken away, of the presser head; Fig. 8 is a detached perspective 30 view of one of the locking dogs; Fig. 9 is a detail sectional view, illustrating the pipe connection to the presser head; Fig. 10 is a view in plan of a portion of the presser head; and Fig. 11 is a plan view of the supplemental board and buckboard.

In its preferred form, the garment pressing machine comprises a hollow standard 1, preferably cylindrical in form and adapted 40 to contain the major portion of the operating parts of the machine. The lower end of the standard is flared outwardly to form a base section 2. The upper end is similarly flared, as at 3, to constitute a support 45 for the main table or top 4.

The numeral 5 represents the buckboard of usual form, and 6 is a hollow horn constituting its support, which in turn is mounted upon the top 4, preferably for vertical adjustment, as will be hereinafter set forth.

To the rear of the standard and bolted

thereto is a forked arm 7 extending above the top 4 and at a considerable distance to the rear of the buckboard 5.

8 represents the presser head mounted upon the forked arm 7 for rocking movement into and out of contact with the buckboard 5.

The operating mechanism for the head 60 comprises a main operating lever 9, in the form of a bell-crank, fulcrumed upon a supporting plate 10 mounted within the base section of the standard and suitably bolted thereto. One arm 11 of the bell crank 65 projects through a slot 12 in the base portion of the standard forwardly of the latter at a sufficient distance therefrom to be conveniently operated by the foot of the user. The complementary arm 13 projects 70 upwardly a considerable distance within the standard, and is purposely enlarged so that in the operation of the machine it will assist in counterbalancing the weight of the presser head.

75 14 is a toggle lever, the members 15 and 16 of which are respectively pivoted to a rearward extension 17 of the tubular member 40 and to the base section of the standard.

18 is a connection between the toggle and 80 the upper end of the arm 13 of the bell crank.

Upon the rocking of the bell crank lever the toggle is straightened sufficiently to throw the presser head into engagement 85 with the buckboard, and the return of the head to its inoperative position upon the releasing of the lever is automatically effected by a spiral compression spring 19 interposed between the arm 13 of the bell 90 crank lever and the front wall of the standard and suitably connected to each. To guard against the overthrow of the head rearwardly through the operation of the spring 19, a tension spring 20 is employed 95 connected to the arm 13 and the standard and acting in the capacity of a cushion to retard the movement of the head beyond the desired point in its elevated position.

10 The presser head heretofore generally referred to is formed preferably in two sections, a head proper 21 and a plate section 22 constituting the pressing surface, and provided with a plurality of apertures 23.

The plate is detachably connected to the head proper by screws 24 and studs 25 that depend from the head section, against which the plate contacts and with which the screws 5 engage, as plainly shown in Fig. 6.

The head described is of a configuration corresponding to that of the buckboard. Within its upper portion and extending longitudinally thereof is a steam inlet chamber 10 26, the lower wall of which is provided with a series of apertures 27 that lead within a main steam distributing chamber 28. Extending longitudinally within the latter chamber is a super-heater 29, in this instance comprising an open-ended cylinder 30 and a burner consisting of an apertured tube 31 extending longitudinally within the cylinder and supported upon a gas conduit 32 leading outwardly through the rear of 15 20 the head to a suitable source of supply.

33 are vent tubes for the burner leading from the interior of the cylinder outwardly through the forward portion of the head, as shown in Fig. 6.

25 The heater described is designed to super-heat the steam, so that it will be delivered through the head in a dry condition to the garment to be pressed. It also serves as a spreading device for distributing the steam 30 from the supply equally over the apertured pressing surface. To accomplish this result, the upper portion of the head is made semi-cylindrical in form, and the cylinder 29 is positioned within the head in proxim- 35 ity to the curved wall thereof, as shown in Fig. 6, so that the steam immediately upon discharging from the chamber 26 will strike the heater and remain in proximity thereto for a short period, and subsequently guided 40 by the heater and the walls of the presser head to the several apertures in the pressing surface or plate 22. The plate is prefer- 45 ably—though not necessarily—slightly con- caved as shown, and to prevent leakage a packing 34 is interposed between the peripheral or edge portion of the head and the plate, as indicated.

In the operation of the machine, it is necessary, for the protection of the cloth or garment that is to be pressed, to cover the pressing surface of the head with a cloth or some other suitable material, the covering being here indicated by the numeral 35. To retain this covering in place, a long spiral 50 spring 36 is provided, and I form a groove or channel 37 in the top peripheral portion of the head of a size to receive the spring, the latter being in the form of an endless ring.

55 60 The marginal edges of the cloth or covering are turned upwardly over the edge of the head and over the groove described, and the spring is pressed within the cloth into the groove, and acts by its tension not only

to hold the cloth in place but to stretch the 65 covering tightly over the pressing surface.

The connection between the head proper and its support 7 is in the form of complementary arms 38 and 39 and a transverse tubular member 40, reference being had particularly to Figs. 2 and 9 of the drawings. A bushing, as 41, is fitted within each end of the tubular member 40, and extends within the tubular bearing 42 formed in the extremities of the fork members of the support 7, constituting the journals on which the member 40 turns. The member 40 is provided with complementary openings 43 and 44. The gas conduit 32 described projects rearwardly of the head within the opening 44 and then transversely through one of the bushings 41. 45 represents the steam conduit communicating with the chamber 26 and projecting similar to the gas conduit to the rear of the head within the opening 43 of the member 40 and outwardly through the remaining bushing 41. These two conduits are adapted to connect, preferably by swivel joints (not shown), with piping leading to steam and gas supplies. 70 75 80 85 90

As steam is only used temporarily in the operation of the machine in the intervals when the head is in operative relation to the buckboard, I have provided controlling means for the steam supply conduit consisting of a valve of any approved type, as 46, normally seated, provided with a spring-pressed stem 47 and an operating lever 48 fulcrumed upon an extension 49 upon the valve casing and projecting forwardly beyond the presser head into position for operation by the operator. I also preferably provide a handle 49^a for the head, by which the same may be operated by hand if desired, or partly by hand and through the agency 95 100 105 of the foot lever previously described.

The horn upon which the buckboard is mounted is also hollow, so that steam may be introduced to heat the buckboard during the operation of pressing. It is held upon the 110 top by means of a bolt 50, the head of which engages a cross bar 51 in the horn, and the shank projects down through an opening formed for that purpose within the top, and is clamped by a nut 52. The bolt as shown 115 is hollow to form a steam inlet, and at its lower end connects with a suitable steam supply pipe 53.

54 is a pet cock for permitting the discharge of the water of condensation. 120

To permit of the pressing of garments or cloth of different thickness, the buckboard is adjustable upon the support or table as previously set forth. This adjustment is effected through the agency of a tubular internally-threaded section 55 formed preferably integral with the buckboard, and a bushing 56 externally threaded to engage 125

the thread upon the member 55. The bushing is formed preferably with openings, as 57, for engagement by a spanner wrench, the adjustment being effected by first loosening 5 the nut 52, then rotating the bushing 56 in a direction to effect the desired adjustment, and afterward re-clamping the parts by movement of the nut into contact with the top.

10 The buckboard is detachably mounted upon the horn, and is held to the latter by a bolt 58. A packing, as 59, is interposed between the board and the upper edges of the horn, as indicated in Fig. 4, for the purpose of preventing leakage of steam, and a covering of cloth as 60 is placed over the buckboard and held thereto in the same manner as the covering for the presser head by an endless coil spring 61, and a groove 62 20 within which the margin of the cloth and spring is adapted to extend.

Where large size garments or large pieces of cloth are to be pressed, it is desirable to provide a supporting surface in addition to 25 that afforded by the buckboard. I have therefore constructed the pressing machine with what may be termed a supplemental table 63 of considerably greater area than that of the buckboard and adapted to supplement the latter. This table is located beneath the board, as shown in Fig. 3, and is cut away at its center as at 64, the opening corresponding in configuration to that of the buckboard, so that the table may be 35 brought upwardly into the plane of the board and to extend in close proximity to the board edges.

The table described is supported upon telescopic posts 66, which project down 40 through the machine top 4 and within the standard to the base section or support 10. The inner sections 67 of the posts are connected to the section 10, while the complementary sections 68 are rigidly secured to 45 the auxiliary table. Springs 69 are housed within the telescopic posts in the ordinary manner, for the purpose of automatically throwing the table upwardly into operative relation to the buckboard.

50 Locking means are provided for holding the table in its operative and inoperative positions, consisting of a weighted transverse arm 70 journaled in the machine standard and carrying a pair of locking dogs 71 55 of the construction shown in Fig. 8. These dogs are adapted to engage the upper members 68 of the telescopic posts in such manner according to the position that the transverse arm is thrown as to hold the table 60 against the tension of its spring in its inoperative position, as indicated in full lines in Fig. 1, or in its upper position as indicated in dotted lines in the same figure, the dog serving in this latter position to prevent the

table from being forced downwardly while 65 in use.

The operation of the machine will be obvious from the foregoing description of its construction. Pressure upon the arm 11 of the bell crank will cause the head to contact 70 with the buckboard. During the operation of pressing, steam is discharged through the under side of the presser head by a proper manipulation of the valve lever 48. Generally, the steam is only allowed to discharge through the head for a very brief period of time, and is automatically cut off by releasing the controlling lever. On re-lasement of the bell crank lever, the head 75 is automatically thrown to its initial position in readiness for a second operation.

Attention is directed to the fact that while I have shown and described a particular form of super-heating device, which I deem the preferable in use, I do not desire to be 85 limited to this particular construction, as other forms of heating appliances may be employed accomplishing the same result. It is also not necessary that the super-heater should form the spreading or distributing 90 means. This is the desirable construction, however, and produces superior results.

What I claim as my invention is,—

1. In a garment pressing machine, the combination with a hollow presser head having a fluid-receiving chamber extending longitudinally thereof, of a casing forming a fluid-distributing member within said head, said fluid-receiving chamber having a plurality of vent openings positioned longitudinally thereof above the distributing member, said casing being separated from the side walls of said head by a relatively narrow space whereby the fluid is directed in opposite directions, an apertured pressing 100 surface in the direct path of the fluid, and a gas burner entirely inclosed within said casing.

2. In a garment pressing machine, the combination with a hollow presser head having a fluid-receiving chamber extending longitudinally thereof, of a fluid-distributing chamber below said receiving-chamber, said last-mentioned chamber having a plurality of vent openings positioned longitudinally 110 thereof communicating with the distributing chamber, a gas burner entirely inclosed within said head, and a drum also within said head inclosing said gas burner, and constituting a deflector for the fluid delivered into the distributing chamber.

3. In a garment pressing machine, the combination of a hollow head having a substantially flat pressing surface and a curved top connecting at its sides with the sides of 125 said pressing surface, the said top having a fluid inlet, a cylindrical casing within the head, the curved surface of which latter con-

stituting with the inner surface of the top a distributing chamber, a partition within the head above said drum, the partition extending from end to end of the head and having apertures therein, and means for introducing fluid into said head above the partition.

4. In a garment pressing machine, the combination of a hollow head having a substantially flat pressing surface and a curved top connecting at its sides with the sides of said pressing surface, the said top having a fluid inlet, a cylindrical casing within the head, the curved surface of which latter 15 constituting with the inner surface the top a distributing chamber, a partition within the head above said drum, the partition extending from end to end of the head and having apertures therein, means for introducing 20 fluid into said head above the partition, and a burner positioned within the drum and extending longitudinally of the latter.

5. In a pressing machine, a presser head having a substantially co-extensive longitudinally extending partition with a series of apertures, an inlet in the head above the partition, a superheating chamber below the partition extending substantially from end to end of the head and separated from the 30 upper wall of the head by a relatively narrow space, said superheating chamber constituting a deflector substantially as and for the purpose specified.

6. In a pressing machine, the combination of a presser head having a substantially flat 35 apertured pressing surface and a longitudinally extending partition with a series of apertures, an inlet in the head above the partition and a distributing wall substantially coextensive with the head but separated from the side and upper walls of the latter by a relatively narrow space and said distributing wall being arranged below the partition and above the pressing surface.

7. In a pressing machine, the combination 40 of a presser head having a longitudinally extending partition with a series of apertures, an inlet in the head above the partition, a superheating chamber below the partition and above the lower surface of the 45 head, the superheating chamber being substantially coextensive with the head and constituting a deflector and being separated from the upper and side walls of the head by a relatively narrow passage, a burner for the 50 superheating chamber, and a support projecting inwardly from the head for the burner, said support constituting an inlet 55 conduit for the burner.

In testimony whereof I affix my signature 60 in presence of two witnesses.

HENRY H. BURNS.
